UNITED STATES PATENT OFFICE.

JAMES ALBERT PRICE, OF NEW ORLEANS, LOUISIANA, ASSIGNOR TO PRICE OIL TANK WORKS, INC., OF NEW ORLEANS, LOUISIANA.

LIQUID-DISPENSING DEVICE.

1,251,281.

Specification of Letters Patent. Patented Dec. 25, 1917.

Application filed August 24, 1916. Serial No. 116,887.

To all whom it may concern:

Be it known that I, JAMES A. PRICE, a citizen of the United States, residing at New Orleans, in the parish of Orleans and State 5 of Louisiana, have invented certain new and useful Improvements in Liquid-Dispensing Devices; and I do declare the following to be a full, clear, and exact description of the invention, such as will enable others skilled 10 in the art to which it appertains to make and use the same.

My invention has reference to liquid dispensing devices designed primarily for use in handling gasoline although its application need not be restricted. The present embodiment of the invention is adapted principally for use along highways and in garages for dispensing gasoline and the object is to provide an extremely simple and 20 comparatively inexpensive yet highly efficient apparatus which may be used for discharging any amount of liquid.

With the foregoing general object in view, the invention resides in certain novel features of construction and in unique combinations of parts to be hereinafter fully described and claimed, the descriptive matter being supplemented by the accompanying drawing which constitutes a part of this application and in which:

Figure 1 is a side elevation of the improved liquid dispensing device, parts being broken away and in section;

Fig. 2 is a detail vertical section of the 35 cap of the vent pipe.

Fig. 3 is a vertical section showing the relation of parts when the service tank is being filled by the siphon; and

Fig. 4 is a similar view showing the 40 relation of parts when discharging liquid.

In specifically describing the construction shown in the drawing above briefly described, similar characters will be placed on corresponding parts throughout the several 45 views and reference will be herein made to the numerous elements by their respective indices. To this end the numeral 1 designates a measuring or service tank which is constantly filled with liquid from a storage 50 or supply tank 2 by means of a siphon 3, the tank 3 being disposed in a lower plane than the storage tank. The leg of the siphon in the storage tank 2 is provided on its 55 lower end with an upwardly opening check valve 4 while the other leg of said siphon

is offset and provided with a cut-off valve 5 disposed above the tank 1. The open free end of this last referred to leg of the siphon 3 is disposed in the extreme bottom of the tank 1 in a plane below the lowest 60 point of movement of the fluid outlet pipe to be hereinafter described, so as to maintain said siphon always filled with the liquid. This, as will be understood, provides a means for automatically filling the tank 1 65 when the valve 5 is opened.

The tanks 1 and 2 and the siphon 3 are adapted to be embedded in the earth below the surface thereof and for the purpose of filling the storage tank 2, a filling pipe 6 70 rises therefrom. To permit air to enter the tank 2 as the liquid is discharged from this tank into the measuring tank 1, a vent pipe 7 rises from said tank 2, the upper end of said pipe 7 having a protecting cap 8 by 75 means of which it may be closed for a purpose to be hereinafter described.

A pipe 9 rises from the tank 1 and is provided at its upper end with a stuffing box 10, said box and pipe receiving slidably 80 therein a lower pipe section 11 which is adapted to be inserted into the tank 1 a number of distances in order that different quantities of liquid may be discharged therefrom. A stuffing box 12 is carried by the 85 upper end of the pipe section 11 and establishes a sliding fluid tight connection between this section and the upper section 13 which telescopes therewith. The section 13 depends rigidly from an appropriate manually operated pump 14 supported upon a suitable base 15 or secured in place in any other appropriate manner. A graduated quantity gage 16 rises from the pump 14 and cooperates with an indicator 17 on the upper end of a vertical operating rod 18 whose lower end is secured to the pipe section 11 or to the stuffing box 12 thereof, said rod having an operating handle 19.

When the handle 19 is raised, for instance, until the indicator 17 is opposite one quart on the scale 16, the lower end of the pipe section 11 will be at such a height in the tank 1 as to only permit the pump 14 to withdraw one quart of liquid when 100 operated. The amount dispensed, however, may be increased by moving the handle 19 downwardly or decreased by shifting said handle upwardly. While the pump is being operated, the valve 5 will be closed to pre- 110

vent continual supply of fluid from the tank 2 to the tank 1. In the present embodiment of the invention, the valve in question is equipped with a vertical operating rod 20 which rises through a pipe 21 and is provided on its upper end with a handle 22. This handle 22 is disposed within the path of the stuffing box 12 carried by the pipe 11, and is arranged at such a point upon the rod 20 that it will be engaged by said stuffing box to completely open the valve 5 when the handle 19 is restored to its normal raised position. When the pipe section 11 is again moved downwardly for the discharge of liquid, the valve 5, owing to its own weight, and the weight of the operating rod 20, closes. It may be thus seen that whenever the tank 1 is discharged of its fluid capacity, the refilling of the same will be automatic 20 as soon as handle 19 is restored to its normal or raised position.

For the purpose of permitting air to enter the tank 1 as the fluid is discharged therefrom, a branch vent 23 leads from the pipe 9 to the vent 7. This vent also allows the escape of air from tank 1 as it is being filled by the siphon 3.

Preferably used in connection with the parts described is a housing 24 which surrounds the leg of the siphon 3 above the tank 1 as well as the lower portions of the pipes 9 and 21, said housing being here shown as an upper compartment of the tank 1 formed by a horizontal partition 24'. The use of this housing, however, is optional and the apparatus will operate to equal advantage without the same.

The pump 14, as above suggested, may be of any of the well known types and in the present showing said pump is provided with a pair of outlets 25 and 26 and with a filter 27 between said outlets and the pump. Outlet 25 terminates in the form of the usual goose-neck 28 while a flexible hose is adapted 45 to lead from the outlet 26 for the purpose of filling receptacles at points rather remote from the apparatus. Gate valves or the like 29 are provided for the purpose of directing the liquid through either of the outlets 25 and 26.

In use, the apparatus will be set up substantially as shown on the drawing and after filling the storage tank 2, the cap 8 will be tightened to temporarily prevent the passage 55 of air through the vents 7 and 23. Operation of the pump will now create a partial vacuum in the tank 1 with the result that liquid will be drawn through the siphon 3 into said tank to fill the same, the valve 5 being then open. The siphon having been 60 thus once started will fill service tank 1, provided the cap 8 is released after starting the siphon to permit air to enter tank 2.

When liquid is to be discharged, the handle 19 is forced downwardly to project the

pipe 11 the required amount into the liquid in the tank 1, the amount of projection being shown by the quantity gage 16 and indicator 17 so that the apparatus may be properly set for discharging a pint, 70 quart, gallon, or any suitable quantity, the amount discharged depending totally upon the distance which the pipe 11 is inserted into the liquid. For instance, if said pipe is projected only into one quart of the contents 75 of tank 1, only this amount will be discharged, but if the pipe in question is moved farther downward, say into a gallon of the liquid, it will be obvious that this gallon will be dispensed. The moment the handle 80 19 is moved downwardly, the stuffing box 12 is moved away from the handle 22 with the result that the rod 20 drops to close the valve 5 as shown in Fig. 4, thus preventing the entrance of liquid from the supply tank 2 into service tank 1 while the liquid is being discharged from the latter. After properly setting the pipe 11, the pump 14 is operated and the required amount of liquid 90 will thus be discharged through the goose-neck 28, this liquid passing through the filter 27 which is of any preferred construction and constitutes no part of the present invention. After a predetermined amount 95 of liquid has been discharged, the handle 19 will be restored to its normal raised position with the result that the stuffing box 12 abuts the handle 22 and raises rod 20 to open the valve 5, as shown in Fig. 3. Siphonic action is thus started through the siphon 100 3 to fill the tank 1 from tank 2, the check valve 4 permitting the free discharge of liquid from said last named tank but obstructing any return of such liquid so that the siphon is constantly filled and in readiness for automatic action each time the valve 5 is opened.

By constructing the improved dispensing apparatus in the manner shown and described, it may be manufactured and marketed at a minimum cost yet will be highly efficient and easy to operate. For these reasons, the construction shown and described constitutes the preferred form of the invention but it is to be understood that within 115 the scope of the appended claims, numerous changes may be made without sacrificing the principal advantages.

I claim:-

1. A liquid dispensing apparatus comprising a service tank and a supply tank located below the surface of the ground, a passage leading from said supply tank to said service tank for normally filling the latter, a cut-off valve for said passage, a pipe rising 120 from said service tank and having at its upper end a stuffing box, a lower pipe section passing slidably through said pipe and the stuffing box thereof for projection different distances into the service tank, said lower 125 pipe

- pipe section also having a stuffing box at its upper end, an upper pipe section received in said lower section and the stuffing box thereof so as to permit said lower section to slide vertically, a pump support, a pump mounted on said support and communicating with said upper pipe section, an operating rod secured to and extending above said lower pipe section and having an indicator 10 at its upper end, a quantity scale with which said indicator coöperates, and a handle on said rod for shifting the same vertically to project the lower pipe section the required amount into the service tank.
- 15 2. A liquid dispensing apparatus comprising a service tank and a supply tank to be located below the surface of the ground, a passage leading from said supply tank to the service tank for normally filling the latter, said passage having a cut-off valve, a pipe rising from the service tank to a point above the ground and having a stuffing box at its upper end, a lower pipe section received loosely in said pipe and snugly in 20 the stuffing box thereof, the lower end of said lower section being adapted for projection different distances into the service tank, and the upper end of said section being provided with a stuffing box, an upper pipe section 25 projecting into said lower section through the stuffing box thereof, a pump support, a pump mounted on said support and communicating with said upper pipe section, means for raising and lowering said lower pipe section to project the lower end thereof the required amount into the service tank, a vent pipe extending laterally from the aforesaid pipe to permit the escape of air from the upper end of the service tank, 30 and an additional vent pipe communicating with said first vent pipe and with the supply tank.
- 35 3. A liquid dispensing apparatus comprising a supply tank, a service tank below the
- same, a siphon leading from the supply tank 40 into the service tank, a pump for withdrawing liquid from the service tank, a valve in the siphon for preventing siphonic action when liquid is being withdrawn by said pump, inlets for both tanks to admit air as 50 the liquid is withdrawn, and means for closing the air inlet of the service tank temporarily to cause operation of the pump to initially start the siphon.
4. A liquid dispensing apparatus comprising 55 a supply tank, a service tank, a passage connecting the two, a valve in said passage, a vertical pipe insertible different distances into said service tank, means for moving the liquid from said service tank through said pipe, and means for automatically opening said valve when said pipe is raised a predetermined amount and for holding said valve open until said pipe is again lowered.
5. A liquid dispensing apparatus comprising 60 a supply tank, a service tank, a passage connecting the two, a valve in said passage, a vertical operating rod rising from said valve for opening the same, a vertical pipe adjacent said rod and insertible different 65 distances into the service tank, means for moving the liquid from said service tank through said pipe, and a lateral projection at the upper end of said valve operating rod, said projection being positioned in the upward path of said pipe, whereby upward movement of said pipe to the maximum, will automatically open the aforesaid valve to permit the service tank to be refilled from the supply tank.
- 70 80
- In testimony whereof I have hereunto set my hand in the presence of two subscribing witnesses.
